Design No. 12,090, dated January 4, 1881.

Cut 239.

UNITED STATES PATENT OFFICE.

H. CLAY BASCOM AND CYRUS A. HODGES, OF TROY, NEW YORK, ASSIGNEES
TO THE N. S. VEDDER PATTERN WORKS, BASCOM, GALBRAITH & CO., OF
SAME PLACE.

DESIGN FOR A STOVE.

SPECIFICATION forming part of Design No. 12,090, dated January 4, 1881.

Application filed November 24, 1880. Term of patent 3½ years.

To all whom it may concern:

Be it known that we, H. CLAY BASCOM and CYRUS A. HODGES, each of the city of Troy, in the county of Rensselaer and State of New York, have jointly invented certain Improvements in Designs for Stoves, of which the following is a specification, reference being had to the accompanying cut, print, or engraving of a stove having our said new design.

1c The design for the legs consists of the crossed bars *a a*, connected at top by the centrally-arched and laterally-straight bars *b*, the sprig and flower ornament *c* on the surface, inclosed by the bars *a a* and *b*, and the ornament *d* pendent from the lower angle of the crossed bars, all shaped and disposed on the swelling surface *e* as represented in the accompanying print.

20 The design for the base-section A consists of the series of alternating ornaments *f* and *g* on a raised molding, *g'*, forming the inner border, the flat surface *h*, the straight flat edged parts *h'*, longer intermediate reversely-curved edge parts *h''*, and the ornamental 25 front valance part *i*, all shaped and arranged in combination so as to appear as represented in the accompanying engraving.

30 The design for the upper portion, B, of the door-frames is composed of the compound sprig ornament *j* on the ground *j'*, having the bottom series of arch-connected pendants *k*, and bordered at top by a bead-molding having the central arch, *l*, straight parts *l'*, concaves *l''*, and straight parts *l''*, with scroll ornaments 35 *m* thereon, all shaped and combined as represented in the accompanying print.

40 The design for the end door, C, consists of the rectangular upper section, D, having the peculiar compound ornament *n* on the middle part of the panel *o*, the zigzag fillets *p* across the corners, with the inner and outer corner ornaments, *p' p''*, and the sprig ornaments *q* along the sides, in combination with the projecting oblong lower section, E, having the 45 panel *r*, with the corner ornaments *r'*, all shaped and arranged together as represented in the aforesaid cut.

50 The design for the front door, F, consists of the upper panel, G, having the series of four apertures, *s*, with straight sides and bottoms and angular tops, and intermediate and lateral sub-panels, having angular fillet-tops

and compound ornaments *s'*, the middle band, *H*, and the lower panel, *I*, having therein the two apertures *t*, with straight bottoms and 55 sides and angular tops, and the intervening and lateral top and bottom ornaments, *u u'*, all shaped and combined so as to appear as shown in the aforesaid engraving.

The design for the cover J is composed of 60 the vertically-concave part *v*, having the reversely-curved and angular fillet-border *v'*, the vertically-convex lower part, *w*, having the series of alternate upwardly-pointing ornaments *w' w''* along its outer border, and the intermediate curved surface *x*, bordered along its inner edge by the fillet *v'*, and having along its outer edge the compound border, consisting of the alternately arched and straight fillet parts *y y'*, with the ornaments *z z'* along the 70 inner and outer edges of the straight fillet parts and the ornaments *z''* under the arched parts, all shaped and arranged together as represented in the aforesaid print.

We do not herein claim the design for the 75 urn K, nor the design for the hearth-valance i.

What we claim as our invention is—

1. The design for the legs, composed of the parts *a a*, *b*, *c*, *d*, and *e*, all shaped and combined as set forth. 80

2. The design for the base-section A, composed of the parts *f g g'*, *h h' h''*, and *i*, all shaped and arranged together as set forth.

3. The design for the upper portion, B, of the door-frames, composed of the parts *j j'*, 85 *k l l' l''*, and *m*, all shaped and combined as set forth.

4. The design for the end door, C, consisting of the parts *D n o p p' p'' q* and *E r r'*, all shaped and combined as described. 90

5. The design for the front door, F, composed of the parts *G s s'*, *H*, and *I t u u'*, all shaped and arranged together as set forth.

6. The design for the cover J, composed of the parts *v v' w w'*, and *x y y' z z' z''*, all 95 shaped and arranged together as described.

In testimony whereof we hereunto set our hands, in the presence of two subscribing witnesses, this 22d day of November, 1880.

H. CLAY BASCOM.
CYRUS A. HODGES.

Witnesses:

JAMES A. GILMAN,
CHESTER BASCOM.
